SEWING MACHINE

John P. Weis, Nyack, N. Y., assignor to Wilcox
& Gibbs Sewing Machine Company, New York,
N. Y., a corporation of New York

Application March 16, 1935, Serial No. 11,488

53 Claims. (Cl. 112—123)

This invention relates to improved sewing machines and particularly to improvements in over-edge sewing machines.

Overedge sewing machines of various types are now in general use in divers trades. Even though most of these machines form a satisfactory over-edge seam, usually separate machines are required for single, double, and triple overedge seams, and usually each has one or more design or operation shortcomings.

It is an important object of the present invention to provide a highly practical and efficient single overedge sewing machine which is equally capable of sewing an overedge seam with single, double, or triple threads and to form different types of double and triple thread seams (e. g. Federal standard stitches 501, 502, 503, 504, and 505). Heretofore it has been customary to provide, purchase, and use separate machines for single, double, and triple thread seam requirements, thus necessitating a very substantial and in some instances prohibitive investment in sewing machines and resulting in both idle and over-taxed conditions with each type of machine dependent upon the daily runs of work.

In overcoming these disadvantages and in meeting this object, the present invention provides a simple and highly efficient single sewing machine capable of forming single, double, and triple thread stitches, with the novel feature of an extremely simple stitch forming mechanism wherein it is necessary only to change the loopers and none of the other operating parts when changing from one to the other of single, double, or triple thread stitches, and to merely regulate the thread tensions when it is desired to alter the type of double or triple thread seam.

It is another very important object of the present invention to provide a sewing machine capable of operating at very high speeds with ease and quietness, and with minimum vibration and wear.

Features of this invention related to the accomplishment of this object include: the provision of an overedge sewing machine with comparatively few parts; and trains of feeding, sewing, trimming, and like mechanisms having few, relatively short and positively driven operating parts.

The usual top operating speed for all previous overedge sewing machines has been around 4000 R. P. M. and they usually fail completely at a sustained speed of 5000 R. P. M. because of vibration, lack of lubrication, and similar factors. Yet, machines embodying the present invention have been operated at both intermittent and sustained speeds of more than 6000 R. P. M. for days, and

at speeds of 7000 R. P. M. and more for less sustained periods with substantially no vibration, wear, or lubrication trouble.

Even though the present invention provides a sewing machine adapted to sew a wide variety of 5 stitches, and to do this at exceptionally high speeds, it is an aim of the present invention to provide a machine that will be small, sturdy, and free of vibration and noise. A complementary aim is to provide a machine which will enclose 10 practically all of its moving parts, and which will not impede the operator in natural working movements.

In many present day overedge sewing machines upper, lower, and intermediate drive shafts 15 are provided. In others, where only one main drive shaft is provided it is: necessarily built up in sections or is wide spaced and yielding between bearings, both factors tending to slow up the machine; or, provided with a separate 20 eccentric for each main mechanism which makes the shaft exceedingly long and the machine exceedingly wide.

It is an object of the present invention to provide a machine with only one drive shaft, which: 25 may be made in substantially one piece; will be sturdy, well balanced, thoroughly lubricated; will be free of vibration, wear, and end play; has a minimum number of eccentrics so that the machine may be small.

Features of the present invention which meet this object include: a ball bearing supported main drive shaft; bearings between each pair of eccentrics to reduce springing and vibration; a drive shaft supporting structure to flood the bearings with oil; the provision of a substantially integral adjustable eccentric on the drive shaft for varying the extent of feed rocking movement; bearings or supports close to the eccentrics so that only one eccentric may be used to drive both the 35 needle operating and the trimming mechanism; and a drive shaft which may advantageously be made from one piece.

Another very important object of the present invention is to provide an improved sewing mechanism wherein the needle, which must always be moved through a considerable path, and the loopers which cooperate therewith, will have a minimum of inertia and overthrow, so that the machine may be operated at high speeds with a 50 minimum of vibration and wear.

The present invention meets this object by providing a sewing mechanism wherein: the needle carrier is of small size and moves through a comparatively small path so that there is no inertia 55

problem; the driving connection is substantially direct; the main pivot of the needle carrier is below the work plate rather than as usual above it, so that there is no danger of oil dropping down onto the work.

5 The structure produces a balanced motion, because the power required to operate the associated trimmer absorbs the racing and accelerated motion of the needle drive between the two power movements; viz., maximum power for the needle comes at both ends of its movement.

10 Another feature of this improved sewing mechanism is that all of the main operating parts of the looper mechanism, section of the sewing mechanism, are driven from the same main drive shaft as the needle, and all the bearings thereof are substantially in a bath of oil. Also, the looper mechanism is such that the change-over to single, double, or triple thread seams may be easily and 15 quickly effected and so that the threading thereof may be done advantageously.

15 Yet another object is to provide an improved trimming mechanism which will be free of vibration, cut clean, be positive in its cutting action 20 and be in absolute synchronism with the needle, and which will retain these desirable characteristics even though it is adjustable relative to the point of needle puncture.

25 In meeting this object the present invention provides three forms of trimming mechanism all 30 of which are driven directly from the needle operating mechanism to have absolute synchronism between the needle and cutter so that there will be no puckering of materials—thereby advantageously dispensing with one crank on the 35 main drive shaft. Also, it provides a trimming mechanism which is easily and positively adjustable laterally relative to the needle and to the line of feed, and wherein the driving connection is near the cutter and remote from the cutter pivot so that vibration is reduced.

40 Dependent upon the article being sewed, and the effect wanted, it is desirable to shift the trimmer and the presser foot device relative to the line of stitching, to have a wide and/or narrow overcast thread, seam, or margin. Heretofore it has been customary to shift the presser and the trimmer individually, by hand and by 45 guessing, and to depend on springs for effecting a movement in one or both directions.

45 It is an object of the present invention to provide a shifting mechanism adapted to: move the presser foot device and trimmer simultaneously; eliminate guessing relative to the extent of shifting; obviate uncertain dependence upon springs or the like; allow the presser device and trimmer to function efficiently in all their working positions; be moved to predetermined or set positions quickly.

50 To meet this object the present invention provides several novel features, viz.: a quickly interchangeable hand and foot control; shifting mechanism dispensing with all springs for advancing and/or returning the presser device and the trimmer; a pointer and graduations to indicate the extent of shifting; a flange and slot connection for both pushing and pulling the presser device and trimmer coordinately.

55 Other objects, features, and advantages will be apparent or will appear hereinafter.

In the drawings which merely illustrate the present preferred form of the invention:

The detailed description which follows is under

35 various headings to facilitate an understanding of the various mechanisms and their mode of operation. The present invention is not limited to the details of construction and arrangement of parts illustrated and described herein, for the invention is capable of other embodiments in whole

40 or part, in sewing machines other than those of overedge type. Therefore the phraseology used is for the purpose of description and not of limitation.

45 Main frame and general structure

The sewing machine embodying the present invention comprises a main frame 50 having a bottom 51, and having front, rear, left side, and right side walls 52, 53, 54, and 55 respectively, preferably forming a reservoir 56 for lubricant 57. A plug 57' may be provided to occasionally draw off the lubricant. A glass insert 58 may be provided to indicate the level of lubricant in the reservoir. Rubber or other resilient plugs 49 in bosses 49' are provided to minimize vibration between the machine and bench.

55 A work plate 60 is supported on the main frame 50 by preferably spaced pivot connections 61, including suitable rearwardly projecting lugs 62 on the main frame 50 and cooperating lugs 63 on the work plate 60 with shoulder screws 64 therebetween, as may be seen best in Figs. 2 and 3. A shoulder 65 on the work plate is adapted to engage the underside of the lugs 62 (Fig. 3) to limit movement of the work plate 60 into a raised inoperative position, as when it is desired to make repairs.

60 It should be noted also that the work plate 60 of the present invention is provided with a plurality of channels, 66, 67, 67', and 68, adapted to very efficiently lubricate the various operating instrumentalities, as will be described much more completely hereinafter. Preferably, the 70 work plate is provided with a depending apron

69 to prevent oil spray from leaking out through the joint between the work plate 60 and the rear wall 53, and particularly to throw the spray between the moving parts within the machine itself.

The work plate 60 may be locked relative to the main frame 50. In its present preferred form (Figs. 1 and 7) this is accomplished by providing a pin 74 in the work table adapted to enter a cooperating aperture in the main frame 50 whereupon a beveled end 74' thereof pushes a catch 75, best seen in Figs. 1 and 7, in a clockwise direction about a pivot 75' against the pressure of a spring 76 until the work plate is fully in the down position, whereupon the catch 75 is urged into a suitable groove in the pin 74 by the spring 76. 10 The wide spaced hinges 61, and the pin connection and catch just described, rigidly support the plate and frame relative to each other and prevent adverse rattling or vibration.

In order to provide an effective oil seal between the main frame 50 and the work plate 60 and also to provide a very effective noise and vibration absorber, the present invention provides a cork, felt or like pad 70, preferably located in a suitable channel 71 in the top edge of the various sides 52 through 55. The underside of the work plate rests upon this pad, which in the concave section 72 (Figs. 7 and 10) of the frame supports the bearing cap 73 and prevents oil leakage past it.

The work plate 60, preferably, and as shown, is adapted to advantageously support a trimming mechanism 77, thread control mechanism 78, a presser device 79, and a trimming mechanism and presser device shifter 80 on its upper side, 20 and to support a main drive shaft 81 and associated needle operating, looper, differential feeding and main driving mechanisms 82, 83, 84, and 85 respectively of its underside. All of these mechanisms will now be described in detail.

40 Main driving mechanism

The main driving mechanism 85, best seen in Figs. 2, 4, 5, 6, 7, 9, and 10, preferably comprises a substantially one piece main drive shaft 81 having a split sleeve bearing 86 near the middle and having a ball bearing 87 at the right side and a similar ball bearing 88 on the left side. The bearings 86 and 88 are supported and clamped in suitable bores 86' and 88' between the work plate 60 and cap sections 89 and 90 of a suspended housing 91 as by screws 92, and the remaining bearing 87 is similarly supported and clamped in a coaxial bore 93 between a cap 73 and the work plate 60 by screws 94.

55 Axial movement of the main drive shaft 81, seen best in Fig. 7, may be prevented by one or more of the following: the ends of the split bearing 86 engaging flanges on the main drive shaft; the flange 95 and pulley hub 96 engaging the bearing 87; the hub 97 and head 98 at the left end of the main drive shaft 81 engaging the bearing 88.

A main drive pulley 99 is secured to the right end of the drive shaft in any suitable manner: for example, and as shown best in Fig. 7, by a set screw 100 sliding in a spline slot 101 to prevent relative rotation, and a screw 102 adapted to prevent relative axial movement.

70 Although it would be possible to have the coaxial section 103, head 98, and eccentric 104 integral with the remainder of the main drive shaft 81, they are preferably made separate and secured into a bore 105 in the left hand end of the main drive shaft by a screw 106 entering a suit-

able spline or hole for relative arcuate locating and a screw 107 to prevent relative axial movement as may be seen best in Figs. 7 and 12. The section 103 is a shank integral with the head 98.

5 Occasionally it may be desirable to effect major changes in the feed. For example, it may be desirable to change the machine from 10 stitches per inch as provided by the control, to 15 stitches per inch. According to the present invention 10 this is accomplished by a slide connection 108, between the eccentric 104 and the head 98, comprising a T shaped tongue and slot connection 109.

A screw 110 associated with the tongue and slot connection 109 and held against axial movement in the large head 98 is provided to regulate the position of the eccentric 104 while a nut 111 and washer 112 at the outer end thereof are adapted to rigidly clamp the eccentric against a face on the head 98 to maintain it in the adjusted position. By tightening the nut 111 lightly a snug slidible fit is provided for the eccentric, in which a screw driver may be passed through a hole 113 in the work plate 60 to adjust the eccentric without lifting the work plate or disassembling the machine. The eccentric 104 is a sleeve adapted to be located various distances from the axis of the main drive shaft and to be snugly or rigidly maintained in the adjusted position.

20 Thus, the present invention provides an adjustable main driving eccentric 104 on the main drive shaft 81 adapted to impart various extents of motion to the feeding mechanism 84, as more fully described hereinafter.

25 Oil retainers 114 may be provided in the ball bearings 87 and 88 to prevent oil from escaping. The bearing cap 13 is provided with a collar 115 extending from within the frame to a position overlying the side wall 55 of the main frame, as 30 may be seen best in Fig. 7, adapted to engage with and rest upon the cork or similar pad 70 underlying it in a channel coextensive with the channel 71. In addition to the adjustable eccentric 104 just described in detail, the main drive shaft is provided with a feed lift crank 116 and an upper looper crank 117 on the left side of the bearing 86 and with a combination needle and trimmer operating crank 118 and a lower looper crank 119 on the right side as may be 35 seen best in Figs. 5, 6, 7, 9, and 10.

Needle operating mechanism

The needle operating mechanism 82 is an especially novel, important, and advantageous part 40 of the present invention and should therefore be particularly noted. It is best illustrated in Figs. 2, 3, 5, 6, 14, and 25 through 29.

45 Because it is necessary to have a needle 120 travel through a considerable path in order to clear the materials during the feeding operation, to pull sufficient thread for succeeding stitches, and to pass completely through the materials in order to cooperate with a lower looper, there is the danger of having the needle carrier of considerable length in order to effect a proper drive. In fact most overedge sewing machines, in which a curved needle is used, have needle carrying arms pivoted as much as three to five inches in back of the needle working point. Consequently, 50 with such a long arm, there is considerable material to be moved each time the needle is reciprocated and the problem of adverse inertia is presented when the machine is operated at high speeds.

55 When long needle carrying arms are provided

there is a danger also of overthrow, excess needle travel, or misalignment of the needle relative to the cooperating loopers due to the natural yielding or vibrating of a long arm when operated at high speeds. Another disadvantage in this usual 5 type of structure is that the needle carrying arm is normally pivoted above the work plate and since it must be lubricated, there is danger of oil dropping or being thrown onto underlying materials. All of these disadvantages are overcome 10 in an efficient manner by the present invention; for the needle operating mechanism 82 in its present preferred form comprises a substantially 15 direct drive for a needle with very short operating connections so that mass and inertia are 20 reduced to a minimum. The structure also produces a balanced motion, desirable for high speed 25 operation. Further, the main pivotal connection for the needle carrier in order to effect arcuate movement thereof, is so constructed that the main bearings thereof have a full force-feed lubrication and because the main pivot thereof is located below the top surface of the work plate there is no danger of oil dripping down onto the 30 materials being sewed.

35 This novel needle-operating mechanism comprises a needle carrier 121 having a preferably integral shaft 123 pivotally supported for arcuate movement in bearings 124 and 125 on the underside of a top housing 126 secured to the 40 work plate 60 by screws 127, as may be seen best in Fig. 31 and also in Figs. 1, 2, 3, 5, 6, and 9. The needle 120 may be clamped in a suitable 45 hole of the carrier arm 122 by a nut 128. The top housing is provided with depending lugs 50 forming the bearings 124 and 125 to pivotally support the shaft 123 of the needle carrier 121. A rearwardly extending arm 129 is secured to the shaft 123 by a yoke 130 and screw 131 to hold an eccentric 132 against the left side of the 55 housing 126 and thereby prevent axial movement.

60 A duct 133, closed at the end by a plug 134, extending through the shaft 123 through a hole 135, joins with the oil groove 68 in the housing 126 and work plate 60 in order to effectively oil the bearings 124 and 125 and the eccentric 132 through suitable oil escape apertures 136, 137, and 138 respectively. If any oil drips out of 65 these bearings it will merely drop onto other operating mechanism or into the reservoir 56, and cannot fall on the work. By having the shaft 70 integral with the needle carrier 121 there is no danger of relative shifting. Since the shaft 123 is, according to the present invention, disposed very close to the path of travel of the materials being sewed and close to the point of stitch formation, the carrier arm 122 may, as shown, be made very small, short, and light.

75 In order to impart oscillatory movement to the needle 120 and carrier arm 122 from the raised inoperative position shown in Fig. 5 to the lowered operative position shown in Fig. 6, the present invention provides a very short crank connection 139 comprising a crank-arm 140 secured to the 80 crank 118 as by a conventional cap 141 and screws 142 and joined by a pivot stud 143 to the rearwardly extending arm 129 as may be seen in 85 Figs. 5, 6, and 9 particularly, thus providing very short and substantially direct driving connections 90 with very little inertia.

Trimming mechanism

95 The trimming mechanism 71 also forms an especially important part of the present invention.

tion and should therefore also be particularly noted. It is best shown in Figs. 1, 2, 3, 5, 6, 25, 26, and 31 in its present preferred form and in Figs. 27, 28, and 29 in two modified forms.

5 The novel construction and means of operation illustrated in Figs. 25 and 27, produce a balanced motion, because the power required to operate the trimmer 77 absorbs the racing and accelerated motion of the needle drive 82 between the 10 two power moments. That is to say, the maximum power in operating a needle comes at both ends of the movement, during the reversal thereof. The tendency is for the parts to overreach their stroke at the reversal of the movement. 15 The idle period of power between the two ends of the stroke is utilized to drive the trimmer. Thus, the needle stroke is harnessed with the load of operating the trimmer absorbing the principal part of the accelerated motion of the needle 20 operation, thereby producing a smooth balanced drive for both the needle 120 and cutter 144. These features of construction assist materially in the attainment of the high speeds accomplished by the present machine.

25 To further illustrate this advantageous feature: the needle movement is approximately 1½", while the movement of the trimmer knives is but ¼". The timed relations of the respective movements are such as to permit the needle to 30 pick up motion through its arc of travel before the trimmer begins its cutting action on the work, as when the eccentric 132 reaches the high point shown in Fig. 5 it moves the needle 120 through a considerable path while the trimmer 35 77 remains substantially stationary.

In Fig. 25, the eccentric or crank 132 oscillates with the needle drive shaft 123. Its position with respect to the connection 140 and the driving arm 129 secured to the shaft 123 is such as to bring about a fair balance of the moving weight of the parts so that at high speed, vibration and noise are almost entirely eliminated.

40 In the preferred form it comprises an upper movable cutter 144 having an adjustable connection 145 with a cutter carrier arm 146 mounted for pivotal and axial movement on a shaft 147 which has pivotal and axial movement in up-standing lugs 148 and 149 on the work plate 60. Although the cutter carrier arm 146 is of substantial length, a driving connection 150 is provided intermediate its length, remote from shaft 45 147 and close to the cutter 144, so that the arm will not yield or vibrate to the same extent as it would if the driving connection 150 extended 50 to the shaft 147 rather than the arm, or were located behind the shaft.

55 A lower cutter 151 (best seen in Figs. 1, 5, 8, and 26) comprises a blade secured in a lower cutter carrier 152 as by a holding screw 153 in a channel 154. Preferably it is provided with an integral finger piece 155 at its lower end adapted to facilitate vertical shifting of the cutter in the channel. The lower cutter carrier is provided with a tongue 156 entering a channel in the underside of the work plate 60 and with a secondary tongue 158 entering a channel 159 in a retaining plate 160 secured to a depending front wall 161 on the work plate (Fig. 5). These channels permit the carrier to be slid transversely 60 relative to the line of feed. A spring 162 secured at one end to the depending wall 161, and at its other end to a pin 163 on the carrier 152 (Figs. 2 and 5) yieldingly pulls and maintains the lower cutter 151 in good shearing engagement with the 65 upper cutter 144. A depending finger 164 on

the upper cutter is always in engagement with the lower cutter 151 so that the spring 162 will not pull the lower cutter out of shearing engagement or into a position directly underlying the upper cutter.

70 The driving connection 150 for the upper cutter 144 is very efficient and advantageous. It comprises a crank arm 165 having a bearing 166 at its lower end adapted to receive the eccentric 132 on the shaft 123 of the needle carrier 121 and at its upper end having a pivotal connection 167 to the cutter carrier arm 146 as by a stud 168 (Fig. 25). The bearing 166 may be made integral with the crank-arm 165 so that the eccentric 132 may be slid into the bearing prior to tightening the arm 129 on the shaft 123.

75 Fig. 31 clearly illustrates how the stud 168 has an axially sliding fit with a bore 169 in the cutter carrier 146 so that the trimming mechanism 77 may be shifted laterally relative to the 20 needle.

80 As the needle carrier 121 is oscillated, the eccentric 132 through the crank-arm 165 imparts absolute coordinate movement to the carrier 146 and cutter 144. Thus, there is no danger of the 25 cutter working at the time the feeding mechanism is advancing the material, which would cause the material to pucker. As the eccentric 132 is given a clockwise movement as viewed in Fig. 5, the crank-arm 165 moves arm 146 and cutter 144 into operative cutting engagement with the lower cutter 151 as shown in Fig. 6, and as the eccentric is given a counter-clockwise movement the crank-arm in turn lifts the cutter into the raised inoperative position shown in Fig. 5. 30 Thus, the present invention provides a very advantageous cutter operating mechanism having a direct operating connection and association with the needle operating mechanism so that there is absolute synchronism between these two. 35 This feature also has the very real advantage of eliminating the need of providing an additional separate crank on the main drive shaft for the trimming mechanism which would tend to increase its cost, necessitate widening the machine, 40 and other similar disadvantages. 45

50 Relatively little movement occurs at the pivotal connection 167 between the crank-arm 165 and the cutter carrier arm 146, and consequently no problem of lubrication is involved. However, at the lower end of the crank-arm there is a considerable extent of movement between the eccentric 132 and bearing 166, and these parts are thoroughly lubricated by the provision of the oil conducting aperture 138 extending from the bore 133 in the shaft 123 (Fig. 25). Thus, the present 55 invention provides a well lubricated and very efficient trimming mechanism 77 which is actuated directly by the needle operating mechanism 82.

60 Figs. 27 and 28 show another form of driving connection for a modified form of trimming mechanism 77a which likewise has the advantages of being driven by the needle operating mechanism 82. This form of the invention dispenses with the eccentric 132 on the needle carrier shaft 123 and with the crank 165 and driving connection 150 just described in detail. Instead, the needle arm 122a itself forms the driving connection 150a for the cutter carrying arm 70 65 146a through the provision of a stud 170 on the upper end of the needle arm adapted to ride in a shaped channel 171 as is clearly apparent in Figs. 27 and 28. This shaped channel is disposed so that when the needle arm 122a is in the raised 75

inoperative position shown by full lines in Fig. 27, it will raise the movable cutter into the inoperative position, and when in the lowered position shown by dot-and-dash lines 172 in Fig. 27, it moves the needle arm into the position shown by dot-and-dash lines, it simultaneously moves the cutter 144 into its lowered operative position. Because the channel 171 has considerable depth it is possible to shift the cutter carrier arm 146a into various lateral positions relative to the needle and still obtain the desirable wide and narrow overedge seams with the various trimmer and presser device adjusting mechanisms herein described.

Fig. 29 shows another modified form of trimming mechanism 171b having the advantage of the first form of trimmer driving mechanism wherein the very short driving connections are provided and wherein the needle operating mechanism serves to drive the trimming mechanism. This modified form of trimmer drive mechanism is closer to that form shown in Figs. 27 and 28 than to the form shown in Fig. 25 since it, too, dispenses with the use of an eccentric 132 and crank arm 165 on the shaft 123 of a needle carrier and provides a direct connection between a modified form of needle arm 122b and modified form of cutter carrier arm 146b.

In detail, this modified form of driving connection comprises a gear segment 173 formed on a hub of the needle arm 122b, adapted to engage with a rack 174 portion of a downwardly projecting finger 175 on the cutter carrier arm 146b. As the needle arm 122b is oscillated in a counter-clockwise direction, the gear segment 173 engaging with the rack 174 lifts the cutter carrier into the raised inoperative position shown in Fig. 29, and when it is oscillated in a clockwise direction the cutter arm 146b is moved to the position shown by dot-and-dash lines 176. The gear segment 173 and rack 174 permit lateral shifting of the cutter carrier 146b relative to the needle.

Presser device

The presser device 78 which may be seen best in Figs. 1, 2, and 3 comprises a carrier 180 secured on a rod 181 by a screw 182, the rod having axial and rotary movement in the upstanding lugs 148 and 149 on the upper side of the work plate 60. As may be seen best in Figs. 1 and 3, the carrier block is provided with a finger 183 having a channel 184 adapted to receive a spring carrier-arm 185 and to locate it against lateral displacement while a screw 186 holds it against vertical displacement relative to the block. Divers presser feet 187 may be secured to the front end of the spring carrier-arm as by a pin connection 188. The long spring 185 enables the presser foot 187 to exert substantial pressure on the materials in their relation with the feed dogs 189 and/or 190 of the feeding mechanism 84, yet enables the presser foot to yield for cross seams, supplementary thicknesses, etc. in the work as it is fed rearwardly through the machine.

The main pressure of the presser foot toward the work plate is accomplished by a coil spring 181 located in a suitable bore 192 in the carrier block 180 as may be seen best in Figs. 2 and 3, preferably having a ball 193 at the lower end adapted to slide over the work plate 60. The bore 192 prevents the spring from tilting and cramping the carrier block, while a screw stud 194 permits various pressure adjustments.

Secondary pressure control is provided by a regulating screw 195 on a finger 186 portion of the

carrier block. This screw may be made long enough to engage the spring carrier-arm 185 and may, as shown, be provided with a lock nut 187 to maintain the screw in adjusted position. This regulating structure also serves the advantageous purpose of preventing adverse strains on the screw 186, since a considerable lifting leverage might be applied thereto because of the substantial length between the screw 186 and the presser foot 187.

In the modified form of presser device 79' shown in Fig. 12B the carrier-arm 185' is in the form of a flat spring clamped in the channel 184 with the screw 186, and having an interponent 188 secured thereto by a screw 189 holding a presser foot 187'. Particularly it provides an auxiliary spring 200 in order to obtain the desirable action of a leaf spring effect between the carrier block 180 and the presser foot 187'. This secondary spring is preferably connected to the carrier-arm 185' in the channel 184 with the screw 186, and is provided with a bowed section 201 under the adjusting screw 185. Spring 200 has an upturned end 202 which bears upon the carrier-arm 185', making it possible to use a much lighter weight material in the spring carrier-arm 185' and thereby obtaining better yielding action in the presser device.

As shown in Figs. 2 and 3, an arm 203 extending rearwardly of the carrier block 180 is provided to lift the presser foot into an inoperative position relative to the work plate 60. Preferably, it is provided with any usual type of foot treadle connection.

The presser devices of the present invention are more completely disclosed in my copending application Serial No. 86,922, filed June 24, 1936.

Trimmer and presser device shifting mechanism

It is extremely desirable in overedge machines to provide mechanism adapted to shift the trimming mechanism 77 and presser device 78 laterally relative to the line of stitching and feed, so that overedge seams of various widths may be obtained. Normally shifting mechanisms for this purpose include cams adapted to move these mechanisms positively in one direction and depend upon springs to shift them in the opposite direction. The present invention provides a direct mechanical connection, dispensing with all springs for this purpose so that the presser device and trimming mechanism are positively moved in both right hand and left hand direction relatively to the line of stitching.

The present preferred form is disclosed in Figs. 1 and 5 and in Figs. 32, 33, and 34 particularly. Shifting of the trimmer mechanism 77 is accomplished through the provision of a flange 206 on a stud 207 adapted to enter a slot 208 in the shaft 147. A screw thread 209 on the stud 207 has a connection with a threaded sleeve 210 adapted to be locked in the upstanding lug 149 by a screw 211. A large knurled head 212 is provided on the stud 207 to manually rotate the screw. When the stud is turned in a right hand direction, the shaft 147 through the flange 206 is moved in a left hand direction to move the trimming mechanism closer to the needle and to the line of stitching and when moved in a left hand direction the flange moves the shaft to the right as viewed in Fig. 32 to shift the trimming mechanism farther away from the needle in order to provide a wide overedge seam.

Coordinate movement and wide and narrow spacing of the presser foot 187 relative to the

needle 120 is accomplished similarly by the same flange 206 engaging a slot 213 in the presser device shaft 181. A finger 214 suitably secured to the top of the upstanding lug 149, as by the screws 211 and 211' or by either one of these when the plate is set in a channel, is provided with an end 214' adapted to cooperate with peripheral groove graduations 215 on the head 212 to indicate the extent of lateral shifting of the presser device 76 and trimming mechanism 77 when the head is rotated.

As shown in Fig. 33 the screw sleeve 210 may be provided with an aperture 216 to receive the point of the screw 211 to prevent it from turning and from moving axially in the bore 217. The head 212 of the screw may be arranged to clear the top of the plate 214 so that it may be tightened against the sleeve 210 to lock the screw stud 209 in the desired position. This latter feature may be improved by having the screw sleeve provided with a slot. The sleeve has a sliding fit with the bore 217 so that it is very easy to change from one type of adjusting mechanism to another.

Fig. 35 shows a modified form of adjusting mechanism 80a which is similar in many respects to that form just described in detail; however, it is arranged for quick foot operation rather than for slow manual or hand operation. The main point of difference in this structure is that the screw stud 209a is provided with a much coarser pitch thread, preferably a double, triple, or quadruple thread, and the head 212a of the screw is provided with an arm 218 adapted to be connected to any usual foot control mechanism as through one or both holes 219 at the outer ends of the lever.

As is clearly apparent in Figs. 35 and 37, the rearwardly extending arm may be provided with a screw 220 adapted to engage the top face of the work plate 60 to limit movement of the stud in a clockwise direction and thereby limit the movement of the flange 206 and related presser device and trimming device, through shafts 147 and 161 respectively, toward the needle, thereby to provide a fixed stop to effect a predetermined narrow width of overedge seam margin. Similarly, a forwardly extending arm 218' on the head of the screw 209a may be provided with a similar adjusting screw 220' adapted to engage the top of the work plate to limit counter-clockwise movement of the screw and right hand travel of the flange 206 so that the presser device and trimming device, through the flange 206, are moved to a predetermined position in order to obtain a predetermined wide overedge seam.

As may be seen best in Fig. 37, a coil spring 221 may be provided between the rearwardly extending arm 218 and top of the work plate 60 in order to maintain said arm in a raised position so that the machine is normally in condition for producing the predetermined width of wide overedge seam. However, when the operator presses down on the foot treadle, the arm 218 presses down on the spring 221 until the screw 220 engages the top of the work plate in order to produce the predetermined width of narrow overedge seam. By moving the coil spring 221 under the forwardly extending arm 218', the reverse effect is obtained.

Somewhat similarly, but by omitting the springs entirely and providing two wires extending from a foot pedal arranged like a first class lever attached on the lower end, and to the forwardly and rearwardly extending arms 218' and

218 respectively, it is possible to easily and quickly move the modified form of control 88 into either the wide or narrow overedge margin forming position without maintaining it in either of these positions against spring pressure.

If preferred, the head 212a on the screw 209a of the modified form of shifter (Fig. 35) may be of two piece construction having a knurled head 222 and a shank 223 accommodating a sleeve 224 which joins the two arms together. With this structure it is possible to effect major adjustments of the shafts 147 and 161 with the flange 206 shifting the presser device 79 and trimming mechanism 77 while the sleeve 224 is loose on the shank 223. When the major adjustment is effected, a screw 225 on the sleeve may be tightened onto the shank, so that the arms 218 and 218' may thereafter be used in order to effect quick shifting into predetermined wide and narrow overedge seam forming positions.

This modified shifter 80a (Fig. 35), similar to the preferred form disclosed in Figs. 32 through 34, also has the advantage of providing a positive and mechanical control for shifting of the presser device and the trimming mechanism into both the wide and narrow seam forming positions and of dispensing with the use of uncertain functioning spring members for this operation. The change from the manual control of Figs. 32 through 34 to the automatic or foot control arrangement of Fig. 35 is effected by merely loosening the screws 182 and 182' of the presser device carrier block 182 and the cutter carrier-arm 146 respectively, and then loosening the screw 211 holding the screw sleeve 210 in order to pull the screw 209 and threaded sleeve 210 from the upstanding lug 149 and to replace these parts on the same shafts 147 and 161 with the modified screw 209a and modified sleeve 210a of that form of the invention shown in Fig. 35. Said screw and sleeve are slid axially into the bore 217 whereupon the sleeve 210a is held in place with the screw 211.

Another modified form of control 80b is shown in Fig. 36 which is very similar to that form shown in Fig. 35, differing mainly in the provision of helical half threads 226 and 227 adapted to engage with angularly disposed slots 228 and 229 in the shafts 147' and 161' respectively and having a shank connection 230 with a plain sleeve 231 rather than the axially moved screw stud 209 connection in the first two forms of the adjusting mechanisms 80 and 80a just described. A collar 232 on the end of the shank 230 prevents axial movement of the stud 209b in the sleeve 231 which is located and held in proper axial position by the screw 211, as shown in Figs. 33 and 34. This form of the invention has the advantage of dispensing with the two part head construction just described in connection with Fig. 35 since major adjustments may be effected by merely shifting the sleeve 231 axially in the bore 217 without turning the arms 218 and 218', then tightening the screw 211.

Feeding mechanism

The object of a differential feed in a sewing machine is to overcome stretching of elastic materials such as knit materials from which sweaters, bathing suits, underwear, and other clothing are made, and also when operating on soft material such as blankets, serges, felts, laces, open mesh, and other articles employing delicate materials that may be condensed or compressed into smaller space than they normally occupy.

The present differential feed is arranged so as

to have a movement approximately three and one-half times greater than the main feed and its motion may be varied during the operation of the machine by the control lever, either by hand, foot 5 treadle, or knee shift. Regardless of the speed of which the machine is operating this shift will change the motion of the feed on the work so as to cause it to gather if the movement of the differential feed is greater than that of the main feed.

10 Suitable feed teeth or surfaces and differences of feed will enable not only gathering, but also shirring of the material or ruffing or pleating, within the limits and scope of the arrangement and design of the parts. That is to say, if the 15 differential feed has but one tooth to contact with the work, it will permit the work or material to fold upon itself, forming distinct ruffles or pleats. If sufficient action be given to the differential feed, a distinct pleat can be effected.

20 On the other hand, if the differential feed contacts with a larger portion of the material, as for instance, several teeth are brought to bear, the effect is a shirring or gathering action, rather than a pleat or fold. The goods is pushed together, so to speak, and that is the desired function in most cases, especially on knitted and other soft fabrics.

Cooperating with the feeds must be a suitable 30 presser foot to hold the materials against the feed, and a great variety of effects can be produced by special designs of presser feet. The length of the foot, the shape of the pattern end, the width of its bearing surface on the goods, and the amount of pressure, all of which must be considered and 35 arranged to bring about the desired function and effect of the differential feed.

The differential feeding mechanism 84 and control mechanism therefor is much more completely described in a copending application Serial No. 40 27,773, filed June 21, 1935, and in the present disclosure, as can be best seen in Figs. 3, 4, 7, 10, 12, 12A, 13 and 18, comprises a feed dog carrier 235 having a pivotal connection 236 with a shaft 237 on a feed rocker frame 238. A primary feed dog 45 189 is secured to the front end of the main carrier 235 (Figs. 4, 7, and 18) with a screw 242 (Fig. 18), and a differential feed dog 190 may also be slidably secured thereto by a screw 243 (Fig. 7). Both feed dogs reciprocate in a slot 244 in a needle 50 plate 245 (Fig. 4). Substantially midway of its length the carrier 235 is provided with a feed-lift connection 246 (Fig. 9) including a split bearing 247 fitting upon the crank 116 of the main drive shaft 81 which in turn slides in an elongated slot 55 248 (Figs. 9 and 18).

A feed rocking connection 249 (Figs. 4, 7, and 12) is provided to impart variable extents of movement to materials on the work plate 60 under the presser device 79 and relative to the needle 120 60 and primary feed dog 189. Main feed rocking movement of the carrier 235 and primary feed dog 189 secured thereto, is effected by a rearwardly extending crank-arm 250 connected to the adjustable eccentric 104 by a bearing 251 at the front end and at the back end by bearing 252 (Fig. 13) to the sleeve shaft 237 or the rocking frame 238 which is pivoted on the sleeve 239 in bearings 240' 65 and 241' on the webs 240 and 241 of the work plate 60. By moving the eccentric 104, less and greater feed rocking movement is imparted to the frame 238 and carrier 235.

In order to effect the major adjustments of the eccentric 104 on the head 98 for various extents of feed, the present invention provides a hole 75

and a slide 113' in the work plate 60 (Fig. 2) so that it is possible to move the adjusting screw 110 (Fig. 4) with a screw driver alone, when the nut 111 is tightened only enough to insure a snug sliding fit rather than a locked fit between the eccentric 104 and head 98 (Fig. 10). When it is desired to have a lock fit, a wrench may be passed down through an opening 183a (Fig. 2). Thus, it is not necessary to lift the work plate whenever major adjustments are made to the eccentric. 10

The mechanism for moving the differential feed dog 190 (Figs. 4, 7, and 10) comprises the mechanism just described and a forwardly extending crank arm 254 connected to the eccentric 104 at one end, and at its other end having a pivot connection 255 with a block 256 slidably mounted on a link 257 (Fig. 4). The upper end of link 257 is connected to a differential feed dog carrier 258, which is slidable in a slot 259 in the main carrier 235. The carrier may be made of two pieces with 20 interchangeable sections 235a held together by screws 235b if preferred. At its lower end the link 257 is pivoted on a stud 261. Divers differential feed dogs 190 may be connected to the differential feed dog carrier 258. 25

Viewing Fig. 4, it will be seen that the connection 254 extending from the driving crank, and the slide block 256 can be shifted up and down on the curved arm 257. When the block is shifted to the highest position on the curved arm, the angular relation of the connection 254 is changed a number of degrees from the position shown. This effects a slight change in timed relation. Instead of the two feeds working in unison or as one feed, when the parts are shifted to the highest position, there is a slight retarded movement to the feed dog 190. The movement is slower than the movement of feed 189 because the crank is operating in a direction towards the top or working surface of the machine. 30

This lifting motion on the bearing end of the connection 254 causes this retarded movement, which has a slight stretching effect on loose and sleazy materials. On the other hand, when the connection is shifted down to its lowest position, 45 there is an advanced timed relation and movement to the differential feed 84 in relation to the main feed 189. This is important to bring about the wide range of effects desired in stitching different kinds of materials. All of these effects are instantaneously produced during the operation of the machine by shifting the lever 271. 50

Since it is important to accurately position the differential feed 190 with respect to the main feed 189, an eccentric bushing 262 (Fig. 10) is provided that fits over the screw 261. This bushing operates in the bearing and is clamped in fixed relation by nut 261' tapped into the curved arm 257. By loosening the nut 261' and turning this bushing, the arced relation of the arm 257 is changed so that as the slide block 256 is shifted up and down, the feed dog 190 may be brought to a position very close to the main feed 189, while in another position, the adjustment of 65 this eccentric bushing will cause a considerable space to be maintained between the back left hand edge of the differential feed 84 and the front right hand edge of the feed 189, leaving a space between the two, which permits goods to 70 expand or enter therebetween as it is carried past the stitching position. Then too, this adjustment is very important when the machine is arranged for making 20 stitches to the inch under certain requirements, or on the other hand, making a 75

long stitch, 5 or 6 to the inch depending upon the requirements. Were it not for this eccentric bushing, the differential feed 84 would require shifting or an endwise adjustment to meet the requirements.

Shifting of the slide block 256 into various stations in order to effect a differential feed is preferably accomplished instantaneously, without the use of hands, and without the necessity of lifting the work plate 60 from the main frame 50 by the provision of a control arm 263 pivotally mounted on a stud 264, having a novel spring strip connection 265 under screws 266 and 267 to the slide block and having a pin and slot connection 268 with a stud 270 and outer lever 271 pivotally mounted on the left side wall 54.

The outer lever 271 may be provided with any suitable foot treadle or knee shifting mechanism, and is also conveniently located for hand shifting, being connected to the front and rear ends 272 and 273 respectively. Regulating screws 274 and 275 in a lug 276 limit the extent of clockwise or counter-clockwise movement of the outer lever and associated slide block 256. A spring 278 may be provided to normally urge the lever and slide block 256 into the maximum feed position when positioned as shown by solid lines, or into minimum feed position when in the dot and dash position shown in Fig. 3, dependent on whether the work is mostly plain or mostly gathered, pleated, or the like. The slide block 256 may be provided with a slightly bowed flat spring 278 (Fig. 18) adapted to press against the link 257 and frictionally maintain the slide in any position on the link that it is moved to. An open side 280 (Figs. 4 and 10) on the slot 281 enables the operator to raise the work plate without use of special tools and without disturbing the adjustment of the regulating screws 274 and 275.

Fig. 12A discloses a modified form of feeding mechanism 84a including a main carrier 235a to which divers primary feed dogs 189a may be secured by screws 282. The crank 250 (Figs. 4, 12 and 18) and frame 238 actuated by the adjustable eccentric 104 form a feed rocking drive. This is an economical feed mechanism to manufacture, for those machines wherein the secondary feed dog 190 and its controls are not needed, as in sewing materials which do not stretch unduly. Jack-screws 282' are provided to tilt the feed dog relative to the presser foot. Section 235a may also be so secured.

Looper mechanism

The looper mechanism may be seen best in Figs. 9, 10, 11, 16, 17, 19, 20, and 31 and comprise a lower looper mechanism 286 and an overedge looper mechanism 287 the latter having a retracted position under the work table 60 (Fig. 10) and an advanced operating position above work table and materials being sewed (Fig. 21). These looper mechanisms are capable of forming a usual single, double, and triple thread seam, type 501, 502, 503, 504, and 505 "Federal specification for stitches, seams, and stitching" shown in Figs. 39, 41, 43, 46, and 45 respectively.

The novel tensioning mechanism 78 described hereinafter assists materially in the formation of these various stitches. The mechanism for the three thread stitch (Figs. 45 and 46) is most completely illustrated in the present drawings and for that reason will be described first.

The lower looper mechanism 286 (Figs. 10 and 17 particularly) comprises a looper carrier arm 288, supporting a looper 289, on a shaft 290 piv-

totally mounted in a bearing 291 of the depending housing 81, and having an arm 292 extending laterally of the machine to a crank connection 293 with the crank 119 on the main drive shaft. Preferably, the connection comprises a crank-arm 294 with a ball and socket joint 295 at the upper end and a similar ball and socket joint 296 at its lower end. The lower looper 289 is secured to the looper carrier 288 by screws 297 and may be readily interchanged for other slightly different shaped loopers when the size of the thread, materials being operated upon, stitch, or other similar factors make such change desirable.

The overedge looper mechanism 287 comprises a looper carrier 298, interchangeably supporting a looper 299, on a shaft 300 shown in Figs. 10, 11, and 16, and which has a secondary arm 301 with a crank connection 302 to the crank 117 on the main drive shaft. The crank connection preferably includes a crank-arm 303 having a ball and socket joint 304 at its upper end to the crank 117 at one end, and a similar ball and socket 305 joint to the arm 301 at its lower end. The shaft 300 is journaled in a bearing 306 of the depending housing 81. The carrier 298 supports a looper 299 on a pivot 307 which has a secondary pivotal connection 308 intermediate its length on a crank-arm 309 portion of a shaft 308' held in place as by a collar 308'. This looper mechanism imparts both a vertical and oscillatory movement to the looper 299; viz. when the crank 117 is in the uppermost position it pulls the crank-arm 303 upwardly and causes the shaft 300 to be moved into its farthest counter-clockwise position wherein the carrier 298 and the lower end of the looper 299 are moved down and wherein the crank-arm 309 is similarly moved down so that the top end of the looper is underneath the work support and is in a retracted position relative to the materials being sewed.

However, when the crank 117 is rotated toward the lower position as viewed in Fig. 10 it imparts a clockwise rotation to the shaft 306 initially lifting the looper 299 to a point above the top of the work plate 60 and then imparting a counter-clockwise movement to the looper in order to move the thread carrying point thereof over the top of the material for well known cooperation with the needle 120.

In general, and dependent upon the type seam desired, the lower looper mechanism 286 may carry a hook-type looper 289', as shown in Figs. 38 and 42, or may be an eye-type looper 289 as shown in Figs. 10, 17, 40, and 44 particularly. Similarly, the overedge looper mechanism 287 may carry a hook-type overedge looper 299', as shown in Figs. 38 and 40, or an eye-type overedge looper 299 as shown in Figs. 10, 16, 42, and 44 particularly.

Thus when the loopers 289' and 299' (Fig. 38) are used, and a thread 310 is carried through the work 311 by the needle 120, the hook-type looper catches the needle loop, carries it to the edge of the material where the overedge hook-type looper 299' catches it in the notch 312 during its upward movement and during retraction of the looper 289' to carry it into the path of the needle to join the stitch type 501, as shown in Figs. 38 and 39.

When loopers 289 and 299' (Fig. 40) are used, the lower looper 289 and a lower looper thread 313 are passed through the loop of the needle thread 310, whereupon the notch 312 of the overedge looper 299' catches the lower looper 75

thread to carry it upwardly over the edge of the work and into the path of the needle 126 to form the double thread seam, type 502, clearly illustrated in Fig. 41.

5 When a lower hooked looper 288' and an over-edge eye-type looper 288 are used, the looper 288' catches the loop of the needle thread 310 and carries it to the outer edge of the work 311 where the overedge looper 288 carrying an upper looper thread 314 passes through the needle loop upwardly over the work and into the path of the needle which, as it passes into the work, catches and holds the looper thread 314 to form the over-edge seam, type 503, shown in Fig. 43.

to the eye 337 in the lower looper 288. Advantageous sights and guides are provided by the present invention to facilitate threading the loopers 288 and 288'. Sights 337a and 337b in the cutter carrier 146 and throat plate 245 respectively (Figs. 5 1, 21, 22, and 26) guide the thread 313, and align the eye 337 for threading. Similarly, a channel 329a and sight 329b, the latter on the throat plate 245, may be used to sight the eye 329 and guide the thread 314 thereto.

10 A single finger 324 on the top of the crank arm 284 oscillates and reciprocates within the guide plates 318, 327, and 331 once each time the needle 126 and loopers are actuated, and in synchronism therewith, to take up the slack 15 thread as the needle and loopers move toward the retracted position. The puller rod or bar 321 causes a slack in the needle thread 310. When the free end 321' is close to the work plate the regulating bar 321 offers very little resistance to 20 the thread and little is pulled from the tension device 338, but when raised it offers more resistance and pulls a greater amount from the tension device. Further, this thread pulling occurs mainly before the needle and thread enter the 25 work so that thread pulling strain is gone while the needle and thread are being forced through the work. The holder 318 is oscillated each time with the cutter rod 147 and may be adjusted with the screw 338 to cooperate with the finger 324 30 so that the latter will pull up slack from the looper rather than from the tension device 316 as the looper 288 is retracted.

35 The slide 336 is provided with a finger 339 so that it is merely necessary to push it to the right 35 as viewed in Figs. 1, 2, and 8 whereupon the eyelet guide 334 is moved from within the frame to outside the frame in order to thread the eyelet guide. Of particular importance, the tension 338 for the needle thread 310 may be of the two station type shown in Figs. 23 and 24, including a plate 340 with pins 341 adapted to enter apertures 342 in the main adjusting nut 343 so that little tension is placed on the thread 310 when these parts are in the station shown in Fig. 23 45 to form the type seam shown in Fig. 45. However, when the fingers 344 of the plate 340 are pushed and turned against a spring 345 to the other station shown in Fig. 24, the greater tension on the thread facilitates the formation of 50 the tight lock-stitch seam shown in Fig. 46.

60 is provided with a series of integral oil directing ducts of large cross section adapted to direct the oil to the various main operating mechanisms. These ducts may be formed by coring the 5 casting or by drilling, and by plugging the outer ends of the ducts. At some points, in fact, oil conduction may be effected by the use of tubes but this adds to the cost of manufacture and presents problems in the way of clearing moving 10 parts, less satisfactory distribution of lubricant to inaccessible places, the possibility of crushing the tube and stopping the flow of lubricant and like disadvantages which are overcome by the channels substantially integral with the work 15 plate as disclosed.

The main distributor channel 67 extends laterally through the back of the work plate as shown in Figs. 2, 4, 5, and 11 in order to direct oil through outlet ducts and ports 67', 68, 376, 20 376, and 377 to the bearings and other underlying operating mechanisms. The ducts and ports are proportioned relatively so that all of the oil cannot escape through any one, but so that there is a substantially even flow in each. Preferably a 25 glass plate 378 is provided at the end of the main channel 67 in order to indicate whether or not the lubricating system is working. The oil port 376 in the middle of this duct 67 and underlying the middle of the glass 378 causes a bubbling of 30 the oil in the middle of the glass and thereby gives the operator a better indication of whether or not, and the extent, oil is being passed. A plate 376a is held by screws 376b.

A web 349 (Figs. 4 and 30) near the outlet 35 port 376, directs oil from the outlet port and drips it onto the eccentric 104 and associated bearings. A similar web 350 directs oil from the port 375 to a channel with outlet holes in the feed dog carrier (Fig. 9) to the feed lift crank 40 116 and associated bearing parts. The duct 68 (Fig. 5) extends from the main channel 67 to a co-extensive channel in the upper housing 91 as may be seen best in Figs. 1 and 5, from whence it is directed through the entrance aperture 135 45 in the rocker shaft 123 of the needle carrier 121 as shown in Fig. 31, and passes lengthwise in the bore 133 in the shaft to outlet apertures 136, 137, and 138 to lubricate the bearings of the shaft 123 and eccentric 132. The arm 130 may be provided with a channel 351 in order to direct oil 50 from the bore 133 to the connection 143 at the top of the crank 140. The channel 68 joins an aperture 352 (Fig. 9) in order to thoroughly lubricate the bearing 86 of the main drive shaft 55 81. The duct 68 may be notched in the bottom of the housing or top of the work plate and a gasket 91a may be provided.

The channel 377 similarly directs oil to the bearing 87. Webs 354, 355, and 356 direct oil 60 from the ports 375 and 376 to the oil entrance apertures 354', 355', and 356'. A channel 67' directs oil to a chamber 91' in the depending support 91 to lubricate shafts 290, 300, and 309. 65 A novel structure is provided for directing the oil 57, from the reservoir 56 in the main frame, upwardly into the work plate 60, even though the latter is movable into a remote or raised position relative to the former; said structure comprising 70 a channel 66 extending downwardly from the work plate to joint with a channel 66' in a cork insert located in a bore 357 of the side wall 55, receiving oil from a pump 358 suitably secured in the side wall. The pump is provided with a 75 pulley 359 (Figs. 7 and 9) adapted to be driven

by the main drive belt which operates the main driving pulley 88. The pump is provided with an inlet tube 360' which extends downwardly into the low point of the reservoir 56 as may be seen best in Figs. 5 and 9. Oil is drawn from the reservoir upwardly through the inlet tube 360' and forced upwardly through the channels 66' and 66 into the main channel 67 for distribution in the manner hereinbefore described. Preferably, a screen 361' is provided near the bottom 10 of the chamber to collect lint, grit, and the like, and thereby prevent such adverse materials from being forced to the bearings of the important moving parts. The normally exposed operating parts above the work plate may be manually 15 lubricated, or may be lubricated automatically by a novel cover 360, in a manner hereinafter described.

Cover

If preferred, all the movable operating parts 20 on the top of the work plate 60, according to the present invention, may be substantially enclosed with a cover 360 in order to protect the operator from the cutter 144, needle 120, and both the 25 needle and trimmer operating mechanisms which are moved at very high rates of speed. The cover also guards against the possibility of an operator dropping a screw driver or any other thing down into the rapidly moving parts. It is 30 particularly advantageous in enabling the operator to use his hands to move the work closer to the operating parts with safety.

The cover may be made of sheet metal, cast 35 iron, or various other materials. Preferably, though, it is made of molded transparent Bakelite, or shaped celluloid, so that it is possible for the operator to thoroughly check up on the operation of the various parts and the movement of the thread and the like through the various 40 guides and tensioning devices, even though the cover encloses all the upper moving parts.

The cover 360 is more completely shown in Fig. 5, and in complementary, though in lesser degree, by dot-and-dash lines in Figs. 1 and 2. It comprises a top 361, front and rear walls 362 and 363, 45 and also left and right side walls 364 and 365. The lower edge of one or more of these walls may be provided with a cushioning member 366, of rubber, leather, or the like to insure a good fit 50 between the cover and the work plate and particularly to prevent the possibility of minor vibrations in the sewing machine being developed into major adverse resonant noises in the cover.

Of particular importance, the inside of the 55 cover 360 is provided with depending webs 380, 381, and 382, as shown by dotted lines in Figs. 1 and 5, which serve to collect the oil vapor which rises out of the work plate opening 324' into drops of oil on tips 383, 384, and 385 adapted to direct the oil, for example, respectively: onto the connection between the needle mechanism and the cutter carrier 146; between the plate 386 and slot 387 of an upstanding finger 388 (Fig. 3); and onto the bearing between the rod 147 and 60 lug 148. Additional tips for collecting and dripping oil onto additional moving parts may similarly be provided. The oil vapor rising out of the opening 324' also very lightly lubricates the threads passing just above it to facilitate their 65 travel in the guides and in needle and looper eyes.

The cover may be held on the work plate in various ways. In its present preferred form it is provided with a snap connection 367 adapted to 70 75

pivotsly secure the rear wall 363 of the cover to the shaft 181 of the presser device between the carrier block 188 and the lug 148. Dot-and-dash lines in Fig. 5 show the cover in the raised or inoperative position, to which it may be easily and quickly moved pivotsly about the shaft when it is desired to make adjustments to the various operating parts or to manually lubricate any of these. As shown in Fig. 1, the front and side walls 362 and 364 are provided with a clearance section 370 extending toward the back of the machine in order to properly clear materials as they are fed rearwardly through the machine.

15 Other variations and modifications may be made within the scope of this invention and portions of the improvements may be used without others.

Having thus described the invention, what is 20 claimed as new is:

20 1. In a sewing machine the combination of a main driving mechanism; a sewing mechanism; a needle rocking shaft in said sewing mechanism; a needle carrier fixed to said rocking shaft, for 25 reciprocating the needle in a curved path; a trimming mechanism including a cutter; a pivoted cutter carrier in said trimming mechanism and means connecting said rocking shaft to said movable cutter carrier, located between the pivot 30 for said cutter carrier and said cutter for coordinate operation of said cutter carrier and said needle carrier.

25 2. In a sewing machine the combination of a main driving mechanism; a sewing mechanism; 35 a needle rocking shaft in said sewing mechanism; a trimming mechanism; a movable cutter carrier in said trimming mechanism; means for shifting the trimming mechanism laterally relative to the sewing mechanism while the latter is in operation; and means connecting said rocking shaft to 40 said movable cutter carrier for coordinate operation and adapted to permit the aforesaid shifting.

3. In a sewing machine the combination of a main driving mechanism; a sewing mechanism; 45 a needle rocking shaft in said sewing mechanism; a needle carrier fixed to said rocking shaft, for reciprocating the needle in a curved path; a trimming mechanism including a cutter; a pivoted cutter carrier in said trimming mechanism; and a crank connection between said rocking shaft and said cutter carrier, located between the pivot for said cutter carrier and said cutter for effecting coordinate operation of said cutter carrier and said needle carrier.

4. In a sewing machine the combination of a main driving mechanism; a sewing mechanism; 55 a needle rocking shaft in said sewing mechanism; a trimming mechanism; a movable cutter carrier in said trimming mechanism; an eccentric on said rocking shaft; a crank-arm on said eccentric; and a pivot connection between said crank-arm and said movable cutter carrier.

5. In a sewing machine the combination of a main driving mechanism; a sewing mechanism; 65 a needle rocking shaft in said sewing mechanism; a trimming mechanism; a movable cutter carrier in said trimming mechanism; an eccentric on said rocking shaft; a crank-arm on said eccentric; means for shifting the trimming mechanism laterally relative to the sewing mechanism; and a pivotal connection between said crank arm and said movable cutter carrier for effecting coordinate operation, and capable of permitting the aforesaid shifting.

70 6. In a sewing machine the combination of a

main driving mechanism; a sewing mechanism; a needle rocking shaft in said sewing mechanism; a trimming mechanism; a movable cutter carrier in said trimming mechanism; and a gear and rack connection between said needle rocking shaft and said movable cutter carrier for effecting coordinate operation.

7. In a sewing machine the combination of a main driving mechanism; a sewing mechanism; a movable needle carrier in said sewing mechanism; a trimming mechanism; a movable cutter carrier in said trimming mechanism; and a gear and rack connection between said movable needle carrier and said movable cutter carrier for effecting coordinate operation.

75 8. In a sewing machine the combination of a main driving mechanism; sewing mechanism; a needle rocking shaft in said sewing mechanism; trimming mechanism; a movable cutter carrier in said trimming mechanism; means for shifting 20 said trimming mechanism laterally relative to the sewing mechanism; and a gear and rack connection between said needle rocking shaft and said movable cutter carrier for effective coordinate operation and for permitting the aforesaid shift- 25

30 9. In a sewing machine the combination of a main driving mechanism; a sewing mechanism; a needle rocking shaft in said sewing mechanism; a needle carrier arm fixed to said shaft, for reciprocating the needle in a curved path; a trimming mechanism including a cutter; a pivoted cutter carrier in said trimming mechanism for reciprocating the cutter; and a pin and slot connection between said needle carrier arm and said cutter carrier, located between the pivot for said cutter carrier and said cutter and providing a cam action for effecting coordinate operation of the needle carrier arm and the cutter carrier.

35 10. In a sewing machine the combination of a main driving mechanism; a sewing mechanism; a pivoted needle carrier in said sewing mechanism for reciprocating the needle in a curved path; a needle carrier arm on said pivoted needle carrier; a trimming mechanism including a cutter; a pivoted cutter carrier in said trimming mechanism for reciprocating the cutter; and a cam connection between said needle carrier arm and said cutter carrier, located between the pivot for the cutter carrier and the cutter for effecting 50 coordinate operation of the needle carrier and the cutter carrier.

40 11. In a sewing machine the combination of a main driving mechanism; a sewing mechanism; a needle rocking shaft in said sewing mechanism; a needle carrier arm on said shaft; a trimming mechanism; a movable cutter carrier in said trimming mechanism; means for shifting said trimming mechanism laterally relative to the sewing mechanism; and a pin and slot connection 55 between said needle carrier arm and said cutter carrier for effecting coordinate operation and capable of permitting the aforesaid shifting.

45 12. In a sewing machine the combination of a main frame; a work table on the main frame; a depending lug on said work table; a sewing mechanism; a needle rock shaft in said sewing mechanism mounted for oscillatory movement in said depending lug below the work table; a main drive shaft; an eccentric on the drive shaft; and 70 a crank connection between said eccentric and said rock shaft.

50 13. In a sewing machine the combination of a main frame; a work table on the main frame; a depending lug on the work table; a sewing mech- 75

anism; a needle carrier in said sewing mechanism movably mounted in said depending lug; a main drive shaft; a crank on said drive shaft; and a connection on said crank adapted to operate said needle carrier.

14. In a sewing machine the combination of a main frame; a work table on the main frame; a sewing mechanism; a needle carrier in said sewing mechanism; a pivot for said needle carrier below said work table; a main drive shaft below the work table; an eccentric on said shaft; and a crank connection on said main drive shaft adapted to operate said needle carrier.

15. In a sewing machine the combination of a frame; a work table on the frame having a raised and lowered position relative to the frame; trimming mechanism including a movable cutter and a normally stationary cutter on the work table; a carrier for the latter; a support for the carrier on the work table; and means adapted to urge the normally stationary cutter into close shearing relationship with the movable cutter when the work table is in both the lowered and the raised position.

16. In a sewing machine the combination of a main frame; a work plate on said main frame; sewing mechanism; a main driving mechanism; a trimming mechanism; a normally stationary cutter carrier; a normally movable cutter carrier; means for shifting the movable cutter carrier laterally relative to the sewing mechanism; and a depending support on said work plate adapted to support the normally stationary cutter and to guide it into various lateral positions for cooperating shearing relation with the movable cutter carrier.

17. In a sewing mechanism the combination of a main driving mechanism; a movable needle carrier; an under looper; an overedge looper; crank driving connections in the main driving mechanism for operating the needle carrier and said looper coordinately; a trimming mechanism; a movable cutter carrier in said trimming mechanism; and a driving connection from said needle carrier to said cutter carrier for operating the cutter carrier coordinately with the loopers and the needle carrier.

18. In a sewing mechanism the combination of a main driving mechanism; a main drive shaft; a movable needle carrier; a crank connection on the main drive shaft for operating the needle carrier; an under looper; only one main pivotal connection for said under looper; a crank connection on the main drive shaft for operating said under looper; an overedge looper; a double main pivot support for the overedge looper, adapted to impart vertical and oscillatory movement to the overedge looper; an eccentric connection on the main drive shaft for operating the overedge looper; a trimming mechanism; a movable cutter carrier in said trimming mechanism; and a driving connection from said needle carrier to said movable cutter carrier for operating the latter synchronously with the loopers and the needle carrier.

19. In a sewing machine the combination of a main frame; a work plate on the main frame; a sewing mechanism; a trimming mechanism; a shaft in said trimming mechanism having a slot; a presser device; a shaft in said presser device having a slot; a rotatable stud; means to prevent axial movement of the stud; and helical flanges on said stud associated with the slots in the shafts, adapted to positively move the trimming

mechanism and the presser device coordinately toward and from the sewing mechanism.

20. In a sewing machine the combination of a main frame; a work plate on the main frame; a sewing mechanism; a trimming mechanism; a shaft in said trimming mechanism having a slot; a presser device; a shaft in said presser device having a slot; and only one member on said work plate cooperating with said slots adapted to move said shafts and associated trimming mechanism and presser device both toward and from the sewing mechanism.

21. In a sewing machine the combination of a main frame; a work plate on the main frame; a sewing mechanism; a trimming mechanism; a shaft in said trimming mechanism having a slot; a presser device; a shaft in said presser device having a slot; a screw in said work plate; and a flange on said screw associated with the slots in the shafts, adapted to positively move the trimming mechanism and the presser device coordinately toward and from the sewing mechanism.

22. In a sewing machine the combination of a main driving mechanism; a sewing mechanism; a trimming mechanism; a rotatable stud adapted to move the trimming mechanism laterally relative to the sewing mechanism; a driving connection between the sewing mechanism and the trimming mechanism for effecting coordinate operation; and only one crank connection on said main driving mechanism adapted to actuate both the sewing mechanism and the trimming mechanism.

23. In a sewing machine the combination of a main driving mechanism; a sewing mechanism; a rockable needle carrier in said sewing mechanism; a trimming mechanism; a presser device; means for concurrently shifting the trimming mechanism and presser device laterally relative to the sewing mechanism while the latter is in operation; a driving connection between the sewing mechanism and the trimming mechanism for effecting coordinate operation; and only one crank connection on said main driving mechanism adapted to actuate both the sewing mechanism and the trimming mechanism.

24. In a sewing machine the combination of a main driving mechanism; a sewing mechanism; a trimming mechanism; a presser device; a rotatable stud for shifting the trimming mechanism and presser device laterally relative to the sewing mechanism; a driving connection between the sewing mechanism and the trimming mechanism for effecting coordinate operation; and only one crank connection on said main driving mechanism adapted to actuate both the sewing mechanism and the trimming mechanism.

25. In a sewing machine the combination of a sewing mechanism including a rockable needle carrier; a trimming mechanism including a rockable cutter carrier; means for shifting the rockable cutter carrier laterally relative to the sewing mechanism; and a driving connection between the sewing mechanism and the rockable cutter carrier to effect coordinate operation and adapted to allow the aforesaid shifting while the sewing mechanism is in operation.

26. In a sewing machine the combination of a sewing mechanism; a needle rocking shaft in said sewing mechanism; a needle carrier fixed to said rocking shaft, for reciprocating the needle in a curved path; a trimming mechanism including a cutter; a pivoted cutter carrier in said trimming mechanism; means connecting said needle rocking shaft to said pivoted cutter carrier, 10-75

- cated between the pivot for the cutter carrier and the cutter for coordinate operation of the cutter carrier and the needle carrier; and means for shifting said trimming mechanism laterally relative to the sewing mechanism.
27. In a sewing machine the combination of a sewing mechanism; a needle rocking shaft in said sewing mechanism; a needle carrier fixed to said rocking shaft, for reciprocating the needle in a curved path; a trimming mechanism including a cutter; a pivoted cutter carrier in said trimming mechanism; a presser device; means connecting said needle rocking shaft to said movable cutter carrier, located between the pivot for the cutter carrier and the cutter for coordinate operation of said cutter carrier and said needle carrier; and means for concurrently shifting said trimming mechanism and said presser device laterally relative to the sewing mechanism.
28. In a sewing machine the combination of a sewing mechanism; a needle rocking shaft in said sewing mechanism; a trimming mechanism; a movable cutter carrier in said trimming mechanism; means connecting said needle rocking shaft to said movable cutter carrier for coordinate operation; and a rotatable stud for shifting said trimming mechanism laterally relative to the sewing mechanism.
29. In a sewing machine the combination of a sewing mechanism; a needle rocking shaft in said sewing mechanism; a trimming mechanism; a movable cutter carrier in said trimming mechanism; a presser device; means connecting said needle rocking shaft to said movable cutter carrier for coordinate operation; and a rotatable stud for concurrently shifting said trimming mechanism and said presser device laterally relative to the sewing mechanism.
30. In a sewing machine the combination of a main driving mechanism; a sewing mechanism; a movable needle carrier in said sewing mechanism; a trimming mechanism; a movable cutter carrier in said trimming mechanism; a rotatable stud adapted to mechanically shift the trimming mechanism laterally relative to the sewing mechanism; and means connecting said movable needle carrier to said movable cutter carrier for coordinate operation and adapted to permit the aforesaid shifting.
31. In a sewing machine the combination of a main driving mechanism; a sewing mechanism; a movable needle carrier in said sewing mechanism; a trimming mechanism; a movable cutter carrier in said trimming mechanism; a presser device; a rotatable stud adapted to mechanically shift the trimming mechanism and said presser device concurrently laterally relative to the sewing mechanism; and means connecting said movable needle carrier to said movable cutter carrier for coordinate operation and adapted to permit the aforesaid shifting.
32. In a sewing machine the combination of a main driving mechanism; a sewing mechanism; a needle rocking shaft in said sewing mechanism; an eccentric on said rocking shaft; a trimming mechanism; a movable cutter carrier in said trimming mechanism; and a crank arm connection between said eccentric and said movable cutter carrier for effecting coordinate operation between the sewing mechanism and the trimming mechanism.
33. In a sewing machine the combination of a main driving mechanism; a sewing mechanism; a needle rocking shaft in said sewing mechanism; an eccentric on said rocking shaft; a trimming mechanism; a movable cutter carrier in said trimming mechanism; a presser device; means for concurrently shifting said trim- 75
- mechanism; a movable cutter carrier in said trimming mechanism; a crank arm connection between said eccentric and said movable cutter carrier for effecting coordinate operation between the sewing mechanism and the trimming mechanism; and means for shifting the trimming mechanism laterally relative to the sewing mechanism. 5
34. In a sewing machine the combination of a main driving mechanism; a sewing mechanism; a needle rocking shaft in said sewing mechanism; an eccentric on said rocking shaft; a trimming mechanism; a movable cutter carrier in said trimming mechanism; a crank arm connection between said eccentric and said movable cutter carrier; a presser device; and means for concurrently shifting the trimming mechanism and presser device laterally relative to the sewing mechanism. 10
35. In a sewing machine the combination of a main driving mechanism; a sewing mechanism; a needle rocking shaft in said sewing mechanism; an eccentric on said rocking shaft; a trimming mechanism; a movable cutter carrier in said trimming mechanism; a crank arm connection between said eccentric and said movable cutter carrier; a presser device; and a rotatable stud for concurrently shifting the trimming mechanism and the presser device laterally relative to the sewing mechanism. 20
36. In a sewing machine the combination of a main driving mechanism; a sewing mechanism; a rockable needle carrier in said sewing mechanism; a trimming mechanism; a movable cutter carrier in said trimming mechanism; a crank connection between said rockable needle carrier and said movable cutter carrier; a presser device; and means for concurrently shifting the trimming mechanism and presser device laterally relative to the sewing mechanism. 30
37. In a sewing machine the combination of a main driving mechanism; a sewing mechanism; a movable needle carrier in said sewing mechanism; a trimming mechanism; a movable cutter carrier in said trimming mechanism; a crank connection between said movable needle carrier and said movable cutter carrier for effecting coordinate operation; and a rotatable stud for shifting the trimming mechanism laterally relative to the sewing mechanism. 40
38. In a sewing machine the combination of a main driving mechanism; a sewing mechanism; a movable needle carrier in said sewing mechanism; a trimming mechanism; a movable cutter carrier in said trimming mechanism; means for shifting said trimming mechanism laterally relative to the sewing mechanism; and a gear and rack connection between said movable needle carrier and said movable cutter carrier for effecting coordinate operation thereof. 50
39. In a sewing machine the combination of a main driving mechanism; a sewing mechanism; a movable needle carrier in said sewing mechanism; a trimming mechanism; a movable cutter carrier in said trimming mechanism; a rotatable stud for shifting said trimming mechanism laterally relative to the sewing mechanism; and a gear and rack connection between said movable needle carrier and said movable cutter carrier for effecting coordinate operation. 60
40. In a sewing machine the combination of a main driving mechanism; a sewing mechanism; a movable needle carrier in said sewing mechanism; a trimming mechanism; a movable cutter carrier in said trimming mechanism; a presser device; means for concurrently shifting said trim- 75

- ming mechanism and presser device laterally relative to the sewing mechanism; and a gear and rack connection between said movable needle carrier and said movable cutter carrier.
- 5 41. In a sewing machine the combination of a main driving mechanism; a sewing mechanism; a movable needle carrier in said sewing mechanism; a trimming mechanism; a movable cutter carrier in said trimming mechanism; a presser device; a rotatable stud for concurrently shifting said trimming mechanism and presser device laterally relative to the sewing mechanism; and a gear and rack connection between said movable needle carrier and said movable cutter carrier.
- 10 42. In a sewing machine the combination of a main driving mechanism; a sewing mechanism; a pivoted needle carrier in said sewing mechanism, for reciprocating the needle in a curved path; a trimming mechanism including a cutter; a pivoted cutter carrier in said trimming mechanism; and an arcuately disposed pin and slot connection between said pivoted needle carrier and movable cutter carrier, located between the pivot for the cutter carrier and the cutter and providing a cam action for effecting smooth coordinate operation of said cutter carrier and said needle carrier.
- 15 43. In a sewing machine the combination of a main driving mechanism; a sewing mechanism; a rockable needle carrier in said sewing mechanism; a trimming mechanism; a movable cutter carrier in said trimming mechanism; a presser device; means for coordinately shifting said trimming mechanism and said presser device laterally relative to the sewing mechanism; and a pin and slot connection between said rockable needle carrier and said movable cutter carrier for effecting coordinate operation.
- 20 44. In a sewing machine the combination of a main driving mechanism; a sewing mechanism; a pivoted needle carrier in said sewing mechanism for reciprocating the needle in a curved path; a trimming mechanism including a cutter; a pivoted cutter carrier in said trimming mechanism; means for shifting said trimming mechanism laterally relative to the sewing mechanism; and a cam connection between said pivoted needle carrier and said movable cutter carrier, located between the pivot for the cutter carrier and the cutter for effecting coordinate operation of said cutter carrier and said needle carrier.
- 25 45. In a sewing machine the combination of a main driving mechanism; a sewing mechanism; a movable needle carrier in said sewing mechanism; a trimming mechanism; a movable cutter carrier in said trimming mechanism; a rotatable stud for shifting said trimming mechanism laterally relative to the sewing mechanism; and a cam connected between said movable needle carrier and said movable cutter carrier for effecting coordinate operation.
- 30 46. In a sewing machine the combination of a main driving mechanism; a sewing mechanism; a rockable needle carrier in said sewing mechanism; a trimming mechanism; a movable cutter carrier in said trimming mechanism; a presser device; a cam connection between said rockable needle carrier and said movable cutter carrier for effecting coordinate operation.

needle carrier and said movable cutter carrier for effecting coordinate operation; and means for concurrently shifting both the trimming mechanism and the presser device laterally relative to the sewing mechanism.

5 47. In a sewing machine the combination of a main driving mechanism; a sewing mechanism; a movable needle carrier in said sewing mechanism; a trimming mechanism; a movable cutter carrier in said trimming mechanism; a rotatable stud for shifting said trimming mechanism laterally relative to the sewing mechanism; and a pin and slot connection between said movable needle carrier and said movable cutter carrier for effecting coordinate operation.

10 48. In a sewing machine the combination of a main driving mechanism; a sewing mechanism; a movable needle carrier in said sewing mechanism; a trimming mechanism; a movable cutter carrier in said trimming mechanism; a presser device; a rotatable stud for concurrently shifting said trimming mechanism and said presser device laterally relative to the sewing mechanism; and a pin and slot connection between said movable needle carrier and said movable cutter carrier for effecting coordinate operation.

15 49. In a sewing machine the combination of a frame; a work table on the frame having a raised and a lowered position relative to the frame; trimming mechanism including a movable cutter and a normally stationary cutter on the work table; a sewing mechanism; means for mechanically shifting the movable cutter carrier laterally relative to the sewing mechanism; and means on said work plate adapted to support the normally stationary cutter and to guide it into various lateral positions for cooperating shearing relationship with the movable cutter carrier.

20 50. In a sewing machine the combination of a work plate; a sewing mechanism; a trimming mechanism; a shaft in said trimming mechanism having a slot; a rotatable stud; and a flange on said stud engaged within said slot to positively move the trimming mechanism toward and from the sewing mechanism.

25 51. In a sewing machine the combination of a plate; a sewing mechanism; a trimming mechanism; a presser device; and a single means adapted to positively move the trimming mechanism and the presser device coordinately laterally toward and from the sewing mechanism and the line of stitching produced thereby.

30 52. In a sewing machine the combination of a sewing mechanism; a trimming mechanism; a shaft in said trimming mechanism having a slot; a screw in said work plate; and a flange on said screw associated with said slot adapted to positively move the trimming mechanism toward and from the sewing mechanism.

35 53. In a sewing machine the combination of a sewing mechanism; a trimming mechanism; and a single screw associated with said trimming mechanism, adapted alone to positively move the trimming mechanism laterally toward and from the sewing mechanism.

40 JOHN P. WEIS.
